UNITED STATES PATENT OFFICE.

GUY W. MERRILL, OF LINCOLN, MAINE.

PRINTING APPARATUS.

1,125,148.

Specification of Letters Patent.

Patented Jan. 19, 1915.

Application filed March 15, 1909. Serial No. 483,415.

To all whom it may concern:

Be it known that I, GUY W. MERRILL, a citizen of the United States, and a resident of Lincoln, in the county of Penobscot and State of Maine, have invented a new and Improved Printing Apparatus, of which the following is a full, clear, and exact description.

This invention relates to certain improvements in printing apparatus, and more particularly to that type of apparatus disclosed in my prior application, Serial No. 423,337, filed March 26, 1908.

One object of my invention is to simplify the operation by providing for the automatic opening of the shutter instead of the manual opening of the same as illustrated in my prior application, and a further object of the invention is to facilitate the transferring of the cards without necessitating the use of an adhesive or gelatinous material.

In both my previous construction and in that illustrated in this application, I provide a combined blank carrier and platen, by means of which the blanks are picked up one at a time and held in engagement with a negative or printing plate. This combined blank carrier and platen is pivotally mounted at the ends of two swinging arms, and occupies a position in substantially a vertical plane while the printing operation is being carried on. After the sensitized blank is pressed into engagement with the negative, it is necessary to open a shutter, or in some other manner permit the light to pass through the negative to the sensitized blank.

An important feature of my present invention relates to the shutter and operating mechanism, whereby the shutter is opened automatically after the combined blank carrier and platen is in operative position. The blank carrier and platen is preferably formed of two separate parts resiliently connected, and the relative movement of one part in respect to the other operates to control the shutter.

Another feature of the invention relates to the construction of these two parts of the blank carrier, whereby their relative movement serves to cause the engagement of the blank with the carrier and its adherence thereto by air pressure.

Reference is to be had to the accompany-

ing drawings, forming a part of this specification, in which similar characters of reference indicate corresponding parts in all the figures, and in which—

Figure 1 is a vertical section through a device constructed in accordance with my invention; Fig. 2 is a vertical section on the line 2—2 of Fig. 1; Fig. 3 is a longitudinal section through the blank carrier; and Fig. 4 is a face view of the blank carrier.

In the specific form illustrated, I employ a horizontal base 10 and a vertical front 11 having an aperture 12, through which the light may pass through the negative to the sensitized blank. The base 10 supports a frame including standards 13 and a rock shaft or pivot 14. A combined platen and blank carrier 15 is secured to a rod 16 slideable through said rock shaft or pivot 14 and movable through an arc determined by two swinging arms 17, 17, each pivoted to the base 10 adjacent its intersection with the vertical front and pivoted to the ends of the blank carrier. To this extent, the device is substantially the same as that illustrated in my previous application above mentioned.

The blank carrier is formed of two separate blocks 18 and 19, arranged parallel and held apart by intermediate springs 20. Screws 21 carried by one block and extending through openings in the other, serve to limit the separation of the two blocks. The center of the block 19 is so constructed that when the block is pressed into engagement with a blank, the blank is caused to adhere to the block by reason of a partial vacuum within the latter. The block 19 has a large conical aperture 22 therethrough and within this aperture is mounted a disk 23 of rubber or the like. The disk 23 is cut from a flat piece of rubber and its normal tendency is to lie in a single plane, but as the springs 20 press the two members 18 and 19 apart, they draw the disk up into the aperture, so that said disk assumes a somewhat conical form. When pressure is applied to bring the members 18 and 19 together, the disk 23 automatically returns to its normal flat position.

The rod 16 by means of which the blank carrier is moved, is hollow and at its lower end it extends through the block or member 18 and terminates within the member 19. The lower end of the rod is open and the disk is secured to the tube, so that the interior of the

22

tube communicates with the hollow conical chamber beneath the disk. The rod is secured to the block or member 18 in any suitable manner, but preferably the latter is threaded, and washers 24 and 25 engage with the block upon opposite sides thereof. The rubber disk is held between one of the washers 25 and a terminal washer 26 disposed within the conical chamber. At the outer end of the rod or tube 16, I provide an air valve of any suitable character, which may be opened manually or otherwise to permit the admission of air. As illustrated, the tube has an opening 27 at its outer end and lugs 28 adjacent the opening. A valve plate 29 normally covers the opening and is carried by a lever 30 pivoted to the lugs. A suitable spring 31 normally holds the valve against its seat.

20 At the outer end of the rod or tube 16 is any suitable form of handle 32, by means of which the rod may be moved longitudinally and may be swung about the pivot 14 as a center. In picking up a blank, the rod is brought to a vertical position, and the carrier is pressed down against the cards within any suitable form of tray or carrier 33. As pressure is applied to the handle 32, the springs 20 are compressed and some of the air beneath the disk 23 is forced outwardly either around the edges or past the valve 29. Upon lifting up on the handle 32, the blocks or members 18 or 19 of the carrier separate and a partial vacuum is created in the chamber or recess beneath the disk. This causes the blank to adhere to the carrier while the latter conveys the card to the negative. For bringing a blank into printing contact with a negative or form to be printed from, a pressure is applied sufficient to insure the proper contact of the blank with the negative or form. This pressure compresses the springs and permits the disk 23 to return to its normal flat position. 45 When the printing operation is completed, the combined platen and blank carrier is moved away from the negative, and, at the same time, the valve 29 is opened to permit air to enter the tube. This destroys the partial vacuum beneath the disk 23, and while the platen is being returned for a second blank, the blank on the platen falls by gravity into a suitable chute or hopper 34 disposed beneath the carrier and in its path 55 of movement. To give the under side of the block 19 a comparatively smooth surface, the portion surrounding the disk may carry a sheet of rubber 35 of substantially the same thickness as the rubber disk 23, and lying in substantially the same plane when the latter is pressed downwardly.

The negative is secured adjacent the inner surface of the vertical front 11 and over the opening 12, and pivoted at the outer side 45 of the opening is a shutter 36 for control-

ling the passage of light through the negative to the sensitized blank. This shutter is preferably pivoted at its lower edge and connected to the pivot is a short arm or lever 37, extending outwardly therefrom. A link 38 is connected to the outer end of this arm and extends through an opening in the front 11 to the lower end of a lever 39 upon the opposite side of the front to the shutter 36. The lever 39 is pivoted to a block 40 and has a laterally-extending end 41 lying in the path of one of the arms 17 which support the blank carrier and define its path of movement. The pivot of the lever 39 is nearer to the upper end than the lower end, so that by a comparatively short movement of the upper end of the lever, the lower end is swung through a wider range and the shutter is operated. The shutter is normally held in closed position by a spring 42, the tension of which is more than sufficient to overcome the weight of the shutter. In swinging the blank carrier into position, the blank comes into engagement and proper registry with the negative before the arm 17 engages with the upper end 41 of the lever 39, to swing the latter. With the blank in position, a slight pressure is applied to the handle 32 and the springs 20 of the blank carrier are compressed. This causes a relative movement of the two blocks or members 18 and 19, and as the arms 17 are pivoted to the rear member 18, the movement of said arms during the compression of the springs 20 swings the lever 39 from the position shown in solid lines in Fig. 1, to the position shown in dotted lines, and the shutter is automatically opened, so that light may pass through the negative to the sensitized blank. No separate operation to open the shutter is necessary, as the mere placing of the blank in position and the continued pressure on the handle 32 operates in itself to open the shutter. As soon as the blank has been exposed for the desired length of time, the operator removes the carrier and the blank is released from the carrier and falls by gravity into the receiver 34. In removing the carrier, the member 18 moves before the member 19, and while this relative movement is taking place and the springs 20 are expanding, the shutter is automatically closing, so that before the blank leaves the negative, the shutter will be closed and there will be no liability of blurring the picture. The relative movement of the members 18 and 19 while the blank is in position, not only serves to open the shutter but also serves to flatten the rubber disk and to insure the perfect contact of the whole of the blank with the negative.

Having thus described my invention, I claim as new and desire to secure by Letters Patent.

1. In a photographic printer, the combination

- tion with a stationary printing plate support, a swinging carrier for presenting blanks to the plate, pivoted arms for guiding the carrier and a shutter coöperating with the support to control the admission of light to the plate, of means for operating the shutter arranged in the path of and adapted to be actuated by the guiding arms of the carrier.
- 16 2. In a photographic printer, the combination with a stationary printing plate support, a swinging carrier for presenting blanks to the plate, pivoted arms for guiding the carrier and a shutter coöperating with the support to control the admission of light to the plate, of means normally tending to hold the shutter closed and operating devices for the latter actuated to open the same by engagement with the guiding arms of the carrier when a blank is presented to the plate.
3. In a photographic printer, the combination with a stationary printing plate support, a swinging carrier for presenting blanks to the plate, pivoted arms for guiding the carrier and a shutter coöperating with the support to control the admission of light to the plate, of means for operating the shutter according to the position of the carrier comprising a crank connected with the shutter, a lever on the support having an arm arranged in the path of the supporting arms and a link connected to the other arm and to the shutter crank.
- 35 4. In combination, a blank carrier formed of two separate members movable in respect to each other, means for supporting a printing plate, a shutter for controlling the passage of light through said plate, and means for controlling said shutter by the relative movement of said members.
5. In combination, a blank carrier formed of two relatively-movable members, means for supporting a printing plate, and means for controlling the passage of light through said plate by the relative movement of said members.
6. In combination, a blank carrier formed of two relatively-movable members, means for supporting a printing plate, means controlled by the relative movement of said members for securing a blank to said carrier, and means for controlling the passage of light through said plate by the relative movement of said members.
7. A printing apparatus, including a wall having an aperture therethrough, means for supporting a negative adjacent said aperture, a shutter pivoted to said wall and controlling the passage of light through said negative, a blank carrier formed of two relatively-movable members and bodily movable in respect to said negative, and means controlled by the relative movement of said members for operating said shutter.
8. In a photographic printer, the combination with a support for the printing plate or negative, of a blank carrier and platen provided with vacuum producing means and an operating member therefor, movable in one direction to control said means and in another to present the carrier to the printing plate.
9. In a photographic printer, the combination with a support for the printing plate or negative, of a blank carrier and platen provided with vacuum producing means and an operating member therefor mounted to swing about an axis to present the carrier to the printing plate and to move radially through such axis to control the vacuum producing means.
10. In a photographic printer, the combination with a support for the printing plate or negative and a shutter controlling the admission of light to the latter, of a blank carrier and platen and an operating member therefor movable in one direction to present the carrier to the printing plate and to a further degree in the same direction to actuate the shutter.
11. In a photographic printer, the combination with a support for the printing plate or negative and a shutter controlling the admission of light to the latter, of a blank carrier and platen and an operating member therefor mounted to swing about an axis to present the carrier to the printing plate and to move radially through such axis to actuate the shutter.
12. In a photographic printer, the combination with a support for the printing plate or negative and a shutter controlling the admission of light to the latter, of a blank carrier and platen provided with vacuum producing means and an operating member therefor movable in one direction to present the carrier to the printing plate and in another to control the vacuum producing means and to actuate the shutter.
13. In a photographic printer, the combination with a support for the printing plate or negative and a shutter controlling the admission of light to the latter, of a blank carrier and platen provided with vacuum producing means and an operating member therefor mounted to swing about an axis to present the carrier to the printing plate and to slide radially through said axis to both control the vacuum producing means and actuate the shutter.
